UNITED STATES PATENT OFFICE.

JAMES EDWIN HILLS, OF NEW YORK, N. Y.

DESIGN FOR A LINK CUFF-BUTTON.

SPECIFICATION forming part of Design No. 31,731, dated October 31, 1899.

Application filed April 25, 1899. Serial No. 714,459. Term of patent 7 years.

To all whom it may concern:

Be it known that I, JAMES EDWIN HILLS, a citizen of the United States, residing at New York city, borough of Brooklyn, in the county 5 of Kings and State of New York, have invented and produced a new and original Design for a Link Cuff-Button; and I do declare the following to be a full, clear, and exact description of the same, reference being had to the accompanying drawings, forming a part thereof.

The accompanying drawings illustrate my design, in which—

Figure 1 is a side elevation, and Fig. 2 a plan view looking from above.

15 This invention relates to a new and original design for a link cuff-button; and it consists of the general outer conformation of the same, as will hereinafter be described.

The characteristic feature of my design consists of the shank, which, viewed from the side, 20 is narrow at one end A and flared upwardly, as shown at B, and downwardly, as shown at C, to form the other end, the downward flare being somewhat longer than the upward flare.

E and F in dotted lines indicate heads such 25 as are used with the shank.

Having thus described my new and original design, what I claim is—

The design for a cuff-button as herein shown and described. 30

In testimony whereof I affix my signature in the presence of two witnesses.

JAMES EDWIN HILLS.

Witnesses:

J. E. PEARSON,
ERNEST V. CLAPP.
